UNITED STATES PATENT OFFICE.

CHARLES M. DODSON, OF DES MOINES, IOWA, ASSIGNOR TO AMERICAN MANUFACTURING COMPANY, OF DES MOINES, IOWA, A CORPORATION OF IOWA.

COIN-CONTROLLED MECHANISM FOR CIGAR-VENDING MACHINES.

SPECIFICATION forming part of Letters Patent No. 758,204, dated April 26, 1904.

Application filed February 8, 1902. Serial No. 92,234. (No model.)

To all whom it may concern:

Be it known that I, CHARLES M. DODSON, a citizen of the United States of America, and a resident of Des Moines, Polk county, Iowa, have invented a new and useful Coin-Controlled Mechanism for Cigar-Vending Machines, of which the following is a specification.

The object of this invention is to provide improved coin-controlled mechanism for use in vending-machines.

My invention consists in the provision of means for testing a "coin" in the machine as to the metal of which it is composed, a magnet being employed to separate the iron or steel disks from those of other metals.

My invention consists, further, in the provision of means for testing a coin in the machine in respect of the resistance of such coin to flexure.

My invention consists, further, in the provision of means for testing a coin in the machine in respect to the thickness and diameter of such coin.

My invention consists, further, in the provision of means for testing a coin in the machine in respect to the quality of the substance thereof, a fork being employed to penetrate and retain a coin made of paper or similar soft and penetrable material.

My invention consists, further, in the provision of means whereby the coin is employed as a necessary part of operating mechanism whereby feeding mechanism is advanced.

My invention consists, further, in the provision of means for closing the coin-slot upon the introduction of a coin thereto and maintaining the slot closed until a complete advance of the feeding mechanism is effected, after which the slot is opened automatically.

My invention consists, further, in the provision of means whereby in the forward movement of a manually-operated lever a coin is tested as to its thickness or diameter and its resistance to flexure and is employed as a part of the operating mechanism and the feeding mechanism is engaged, and in the rearward movement of such lever the feeding mechanism is advanced and the coin released from the

operating mechanism and deposited in the receptacle provided therefor.

My invention consists, further, in the construction, arrangement, and combination of elements hereinafter set forth, pointed out in my claims, and illustrated by the accompanying drawings, in which—

Figure 1 is a front elevation of the coin-controlled mechanism and the means employed to test the coin. Fig. 2 is a left side elevation of the coin-controlled mechanism. Fig. 3 is a rear elevation of a portion of my machine. Fig. 4 is a detail vertical section of the device. Fig. 5 is a similar elevation of the elements shown in Fig. 3, some of said elements shown in different positions. Fig. 6 is a plan of the devices shown in elevation 60 in Figs. 3 and 5. Fig. 7 is a detail perspective of a portion of the mechanism. Fig. 8 is a detail vertical section, on an enlarged scale, of portions of the mechanism. Fig. 9 is a cross-section above the coin-rest. 70

The mechanisms and elements illustrated, described, and claimed herein are designed to be employed in conjunction with other mechanisms and elements illustrated and described in companion applications for patents pending 75 concurrently herewith.

In the construction and mounting of the machine, as shown, the numeral 14 designates a back plate, designed to form the back closure of a casing, of which the plate 81 forms one 80 side wall. Brackets 82 83 are mounted on and project forward from the back plate 14 parallel with each other. A crank-shaft 84 is mounted for rotation in the lower forward portions of the brackets 82 83 and extends 85 through the wall 81 of the casing. The crank 85 of the shaft 84 is in a plane between the brackets 82 83, and a winch 86 is mounted on the outer end portion of said shaft outside the casing. A guard 87 is mounted on the wall 90 81 of the casing and is shaped and arranged to limit and determine movements of oscillation of the winch 86 within a predetermined arc. A counter-shaft 88 is mounted for rotation in the lower ends of the brackets 82 83 95 parallel with and at the rear of and below the

crank-shaft 84. A convolute spring 89 is mounted around one end portion of the counter-shaft 88 and has its outer end portion fixed to the back plate 14 and its inner end portion fixed to a drum 90, loosely mounted on said shaft. A ratchet-wheel 91 is mounted rigidly on the counter-shaft 88 adjacent the drum 90, and a spring-pawl 92, pivoted on said drum, engages said ratchet-wheel and connects the drum and shaft in such manner that by rotating the drum in one direction on the shaft the tension of the spring 89 may be increased. An arm 50 is mounted on the inner end portion of the counter-shaft 88 and extends forwardly therefrom, and a link 49 is pivoted at one end to and rises from said arm to a point of attachment with the feeding mechanism described and illustrated in one of my other applications. A coin-holder and anvil 93 is formed of a steel bar pivoted at its upper end on a shaft 94, journaled in the upper portions of the brackets 82 83. The coin-holder and anvil 93 depends from the shaft 94 nearly to the counter-shaft 88 and is provided with a forked arm 95, extending rearwardly from its lower end portion. A pin 96 is mounted transversely of and connects the rear ends of the forked arm 95 and traverses a segmental slot 97 in a plate 98, fixed rigidly to and extending rearwardly from the counter-shaft 88. A ratchet tooth or shoulder 99 is formed on the rear curved margin of the plate 98 and is arranged to be engaged at times by a hook 100, rigidly mounted on a pivot 101, journaled in a bearing 102, fixed to and projecting forwardly from the back plate. A spring 103 is mounted on the pivot 101 and bears against the bearing 102 in such a manner as to press the hook 100 forward. A releasing-arm 104 is mounted rigidly at one end on the central portion of the pivot 101 and extends forwardly and upwardly therefrom above the counter-shaft 88 to a point of support on the grooved periphery of an eccentrically-mounted disk 105 on the crank-shaft 84. The coin-holder and anvil 93 extends above the shaft 94 nearly to the top of the brackets 82 83 into a notch in the lower margin of a slotted coin-guide 106, mounted horizontally on the front of said brackets and vertically slotted for the passage of a coin therethrough. The front face of the holder or anvil 93 is normally in the same vertical plane as the rear wall of the slot of the coin-guide, and when the lower end of said holder or anvil is moved rearwardly the upper end thereof moves forwardly and obstructs said slot. A yoke 107 is fixed to and depends from the central portion of the coin-guide 106 and is notched at its upper and lower end portions. Wings are formed on and extend rearwardly from the lower portions of the side margins of the yoke 107 and embrace the coin-holder and anvil 93 loosely, being spaced apart a distance equaling the

machine. The lower portion of the yoke 107 is spaced apart from the front face of the coin-holder and anvil a distance equaling the thickness of a proper coin to be used in the machine. A notch 108 is formed in the front face of the coin-holder and anvil 93 immediately at the rear of the notch in the lower portion of the yoke 107. A coin-rest 109 is hinged at one end to the bracket 83 and closes against a stop 110 on the bracket 82 at its other end. A lip 111 is formed on and extends rearwardly from the hinged end portion of the coin-rest 109 and is engaged by an expansive spring 112, fixed to the bracket 83, the tendency of which spring is to push the lip from the bracket and close the coin-rest against the stop 110. A rib 113 is formed on the inner face of the coin-rest 109 and extends from said coin-rest nearly to the forward face of the coin-holder and anvil 93. The rib 113 is arranged vertically across the rear face of the coin-rest 109 and tapers out at its upper end immediately below the notch 108 in the coin-holder and anvil. A lip 114 is formed on and extends rearwardly from the stop 110, adjacent the inner face of the bracket 82. An actuating arm or lever 115 is provided and pivoted at its upper end by rigid mounting on the shaft 94. The actuating-arm 115 extends forwardly from the shaft 94 and then is turned or bent abruptly and extends downwardly and forwardly beyond the crank-shaft 84. The upper end portion of the actuating-arm 115 is forked to embrace the yoke 107 and the lower end portion of said arm is forked to embrace and slide upon the crank-pin 116 in the extremity of the crank 85. A punch 117 is mounted in and extends rearwardly from the actuating-arm 115 and is arranged to move in the movement of said arm through an arc intersecting the notch in the lower portion of the yoke 107 and the notch 108 in the coin-holder and anvil 93. A stud 118 is formed on and extends rearwardly from the actuating-arm 115 below the punch 117. The length of the punch in relation to the length of the stud is such that when there is no coin in the yoke and in the path of travel of the punch said punch will enter the notch 108 and the stud will engage the face of the coin-holder and anvil 93; but when a coin is dropped into the yoke and covers the notch 108 said punch will engage said coin and prevent the engagement of the stud with the coin-holder and anvil. A hook 119 is pivoted at one end on the actuating-arm 115 and is spring-pressed downwardly. The hook 119 is arranged to move in the rearward movement of the actuating-arm through an arc and across the free end portion of the coin-rest 109 and ride on the upper edge of the lip 114 of the stop 110. Upon moving rearwardly the hook 119 engages at the rear of the free end portion of the coin-rest 109 and in its return movement swings said coin-rest away from the stop 110 and coin-holder and anvil against the resilience

of the spring 112. The hook continues to swing the coin-rest forwardly until released therefrom by riding up and over the inclined upper edge of the lip 114, at which time the 5 coin-rest is returned by the spring 112. Plates 120 121 are fixed to the shaft 94 adjacent the side faces of the upper end portion of the coin-holder and anvil 93, and when the elements are in the positions to receive a coin in 10 the yoke 107 the front margins of said plates are flush with the front face of said coin-holder and anvil. In the rearward movement of the lower end portion of the actuating-arm 115 the shaft 94 is oscillated and the upper 15 end portions of the plates 120 121 are tilted forwardly across the slot in the coin-guide 106, as shown by dotted lines in Fig. 8, thus preventing the passage of a coin through said coin-guide at a time when the coin-rest 109 20 may not be in position to receive and retain a coin.

A coin-receiver is mounted on the top of the casing and communicates with the interior thereof through a slot in said top. The coin- 25 receiver is composed of parallel side plates 122, spaced apart a short distance only and connected by end pieces 123 124, and the top of the space between said side plates is closed at either end by pieces 125 126, the space between the latter pieces forming a slot for ingress to the receiver. The receiver is so mounted on the casing that the coin-ingress slot therein is a little to the right of the vertical plane of the slot in the coin-guide 106, 30 and a partition 127 rises in the receiver at the right end of said coin-guide. A slide-seat 128 is mounted horizontally in the receiver and leads to the right from the upper end of the partition 127. A coin-slide is slidingly 35 mounted on the slide-seat 128 and between the side plates of the receiver and is provided with a coin-pocket 130 in its left end portion, normally registering with a coin-slot in the upper edge of the receiver. A thumb-piece 40 or lug 131 is fixed to and rises from the receiver at the right of the coin-slot therein, and a mating thumb-piece or lug 132 is fixed to and rises from the coin-slide 129 at the right of the lug 131. An expansive spring 45 133 is mounted between and fixed at one end to the side plates 122 of the receiver and is connected at its other end to the right end of the coin-slide 129. It is the function of the spring 133 to move the coin-slide 129 to the right into 50 position for the insertion of a coin therein. A detent 134 is pivoted at one end to the side plates 122 of the receiver and is normally pressed upwardly by a spring 135. The detent 134 is formed with an upwardly-extending lip 55 136 on its right end arranged to engage the right end of the coin-slide 129 when said slide is moved to the left by manual force applied to the lugs or thumb-pieces 131 132 and retain the said slide temporarily. A link 137 is 60 pivoted at one end to and depends from the

right end of the detent 134, and the lower end of said link is connected by a wire 138 to a staple or pin 139, mounted in and projecting radially from the crank-shaft 84, whereby in the rearward movement of the winch 86 said wire 70 and link will exert a draft on the detent and release it from the coin-slide. A fork or pin-plate 140 is mounted horizontally between the side plates 122 of the receiver. One end portion of the fork 140 extends through the left 75 end of the coin-slide 129 and intersects the coin-slide therein, and the other end thereof is slidingly mounted in a bearing 141 between the side plates. A shoulder 142 on the fork 140 insures the movement of said fork to the 80 right coincident with the movement of the coin-slide 129 to the right, and said fork may move to the left through the bearing 141 under pressure of a coin against the points of the pins 143, projecting to the right into the 85 coin-slot. A spring 144 presses upwardly against and slidingly engages the fork 140, thus applying a tension to said fork. A horse- 90 shoe-magnet 145 is mounted between the side plates of the receiver with its poles contiguous to the path of travel of a coin from the coin-slide 129 to the coin-guide 106. A trough 146 is mounted in an inclined plane in the casing and leads from the coin-guide 106 laterally outside the casing. The upper end of the 95 trough 146 is open and is below and in the vertical plane of the horseshoe-magnet 145.

There are times, such as when the vending-machine is empty, when it is desirable to prevent the insertion of a coin in the coin-controlled apparatus. For such purpose I have provided a latch 147 of such length as to fit snugly between the lugs or thumb-pieces 131 and 132 when said lugs are separated. The latch is hinged at one margin to the rear side 100 plate 122 and is formed with a staple or eye 148 on its rear face. The latch is provided with a spring 149 at its point of hinging, the tendency of which spring is to lift said latch and cause it to enter and remain in the space 105 between the lugs 131 and 132 and prevent an approximation of one to the other. A key 150 is mounted for vertical rectilinear reciproca- 110 tion in a slide-bearing 151, mounted on the rear face of the rear side plate 122, and a downwardly-opening hook 152 is formed on the upper end of said key and is arranged to engage in the staple 148 on the latch and hold said latch open, as shown in Fig. 3. An arm 153 is formed on the opposite end of the key 150 115 and is pivotally connected to one arm of a lever 154, fulcrumed on the rear side plate 122. The opposite end of the lever 154 is pivotally connected to the upper end of the draft-wire 35, described in one of my other applications 120 as attached indirectly to the commodity being delivered by a vending-machine. A stop 155 on the rear side plate 122 determines the downward movement of the key 150, and a re-tractile coil-spring 156 is attached at one end 125 130

to the lever 154 and at the other end to the side plate and tends to move the lever and key downwardly in opposition to the draft of the wire 35.

- 5 In the practical operation of this coin-controlled apparatus the parts are first positioned as shown. Then a coin 157 is inserted in the coin slot or pocket 130 and rests on the slide bar or seat 128. The operator then grasps 10 the lugs or thumb-pieces 131 and 132 and approximates the latter to the former, thus pushing the coin-slide 129 to the left into the position shown by dotted lines in Fig. 1, carrying the coin with the slide. The coin first engages 15 the needles 143 of the fork 140 and if made of paper or similar fibrous or penetrable material is impaled on said needles and can proceed no farther into the machine. Thus is the coin tested as to its penetrability and fibrous- 20 ity. If the coin is of hard or relatively impenetrable substance, it will push the fork ahead of it and upon passing beyond the partition 127 will fall from the coin-slide. If the coin is made of steel, iron, or similar sub- 25 stance, it will be attracted to the poles of the magnet 145 and roll around the extremity of the lower arm thereof and fall by gravity into the trough 146 and be conveyed outside the casing. In such manner is the coin tested as 30 to the kind of metal of which it is composed and if improper is prevented from operating the apparatus. If the coin be of a metal not attracted by the magnet 145, it will pass into the coin-guide 106 and if not of too great 35 thickness or diameter will pass through said coin-guide into a position within the yoke at the rear of the notch in the lower portion of the yoke and in front of the notch 108 in the face of the coin-holder and anvil 93, supported 40 by the coin-rest 109. If too thin, the coin will slip through the space between the face of the anvil and the rib 113 or tilt backward without permitting the operation of the machine. If too thick, the coin may tip forward and prevent 45 the operation of the machine. If of proper size, the coin will be stopped on the coin-rest 109 directly in front of the notch 108. The operator then moves the winch 86 forward and downward until it is stopped by contact 50 with the lower bar of the yoke 87, thus rotating the crank-shaft 84. In the forward movement of the coin-slide 129 the detent 134 engages its rear end and holds it against reverse movement, thus preventing the insertion of another 55 coin. Now in the rotation of the crank-shaft 84 backward draft is applied to the wire 138 and link 137 to the end of releasing the detent from the slide, and the spring 133 returns the slide to its normal position in readiness 60 to receive another coin. In the rotation of the crank-shaft 84 the crank 85 thereof acts upon and moves the actuating-arm 115 rearwardly, thus bringing the punch 117 into contact with the coin. If the coin be a "five-cent 65 nickel" of United States mintage, it will resist

the action of the punch and not flex; but if made of lead, brass, or other base metal not attractive to the magnet it will be flexed, bent, curved, or penetrated by the punch. This is true for the reason that the coin-holder and anvil is backed by the resilience of a strong spring 89 and will yield only when sufficient pressure has been applied to bend such baser metals, and the notch 108 in said coin-holder and anvil lends to the possibility of such bending. 70 If the coin bends or flexes, it will clog temporarily in the machine and will not offer such thickness between the punch and holder and anvil as is necessary for the proper operation of the machine. If the coin does not 80 flex and has met successfully the other requirements of the other tests, it may be assumed to be a "nickel" of United States mintage and a proper coin to be employed to operate the mechanism. If the coin does not 85 flex, it forms a connection between the punch and holder and anvil and moves said holder and anvil rearwardly, at the same time holding the actuating-arm in such relation to the holder and anvil that the extremity of the 90 stud 118 is spaced apart from and does not contact with the holder and anvil. In the rearward movement of the holder and anvil the pin 96 on the extremity of the forked arm engages and rotatably moves the plate 98 on 95 the counter-shaft 88, thus rotating the counter-shaft against the resilience of the spring 89. In the rotation of the counter-shaft 88 the arm 50 is raised for engagement with a ratchet-wheel, whereby the feeding mechanism, described in my other application, is operated. If the link 49 and arm 50 are not raised to the required altitude, the ratchet-wheel will not be engaged operatively. Herein is to be found the reason for interposing a 100 non-flexing coin between the punch and anvil—namely, that the stroke may thereby be lengthened to the extent of the thickness of a coin and the counter-shaft be rotated enough to lift the arm 50 and link 49 to the 105 desired degree. Thus is the thickness of the coin definitely measured and tested. If too thin, the machine cannot be operated through its use. If too thick it cannot enter to the point of use, and if no coin enters to the point 110 of use the punch will enter the notch 108 without moving the anvil, and the stud 118 is too short to effect the required depression of the holder and anvil. In the rearward movement of the plate 98 the shoulder 99 thereon is engaged by the hook 100 and held temporarily. In the rearward movement of the lower end of the holder and anvil under pressure of the stud 117 the upper end thereof moves forwardly across the lower edge of the coin-guide, 115 and the corner 93^a thereof being sharp would cut off a wire or string that might be attached to the coin to draw it back after use, thus preventing another species of fraud against the machine. The operator now moves the winch 120 125 130

86 forward and upward to the limit of its movement. The first effect of such movement is to position the plates 120 121 for release of the coin and the release of a base 5 coin by reason of the hook 119 pulling forward the coin-rest 109 and permitting the coin to drop into the lower portion of the casing, where it is inaccessible to the operator. The second effect of the upward movement 10 of the winch is the release of the plate 98 from the hook 100 by reason of the rise of the releasing-arm under the actuation of the eccentrically-mounted grooved disk 105 on the crank-shaft and the consequent release of the 15 counter-shaft 88. Upon the release of the counter-shaft 88 the spring 89 exerts its resilience to the rotation of said shaft and the reverse or downward movement of the arm 50 and link 49, resulting in an actuation of the 20 feeding mechanism above referred to. The third effect of the upward movement of the winch is to reposition all the operative parts for a repetition of the operations above described.

25 I claim as my invention—

1. In a coin-controlled mechanism for cigar-vending machines, a coin-holder and anvil, a rock-shaft, arranged for actuation in one direction by said coin-holder and anvil and 30 spring-actuated in the opposite direction, means for connecting said rock-shaft to a feeding device, locking mechanism engaging said rock-shaft against the resilience of its spring, an actuating-arm arranged for engagement 35 with a coin, and means for oscillating said actuating-arm.

2. In a coin-controlled mechanism for cigar-vending machines, a coin-holder and anvil, a rock-shaft arranged for actuation in one direction by said coin-holder and anvil and 40 spring-actuated in the opposite direction, means for connecting said rock-shaft to a feeding device, locking mechanism engaging said rock-shaft against the resilience of its spring, 45 an actuating-arm arranged for engagement with a coin, a crank-shaft arranged to engage and oscillate said actuating-arm and a cam on said crank-shaft arranged to release said locking mechanism.

50 3. In a coin-controlled mechanism for cigar-vending machines, a coin-holder and anvil, a rock-shaft arranged for actuation in one direction by said coin-holder and anvil and spring-actuated in the opposite direction, 55 means for connecting said rock-shaft to a feeding device, spring-actuated locking mechanism engaging said rock-shaft against the resilience of its spring, an actuating-arm arranged for engagement with a coin, a crank-shaft arranged to engage and oscillate said actuating-arm and a cam on said crank-shaft arranged to release said locking mechanism.

60 4. In a coin-controlled mechanism for cigar-vending machines, a coin-holder and anvil, a 65 coin-rest adjacent said coin-holder and anvil,

a rock-shaft arranged for actuation in one direction by said coin-holder and anvil and spring-actuated in the opposite direction, means for connecting said rock-shaft to a feeding device, spring-actuated locking mechanism 70 engaging said rock-shaft against the resilience of its spring, an actuating-arm arranged for engagement with a coin, a crank-shaft arranged to engage and oscillate said actuating-arm and a cam on said crank-shaft arranged to release said locking mechanism. 75

5. In a coin-controlled mechanism for cigar-vending machines, a coin-holder and anvil, a spring-held coin-rest adjacent said coin-holder and anvil, a rock-shaft arranged for actuation 80 in one direction by said coin-holder and anvil and spring-actuated in the opposite direction, means for connecting said rock-shaft to a feeding device, spring-actuated locking mechanism engaging said rock-shaft against the resilience of its spring, an actuating-arm arranged for engagement with a coin, a crank-shaft arranged to engage and oscillate said actuating-arm and a cam on said crank-shaft arranged to release said locking mechanism. 85

6. In a coin-controlled mechanism for cigar-vending machines, a coin-holder and anvil, a spring-held coin-rest adjacent said coin-holder and anvil, a rock-shaft arranged for actuation 90 in one direction by said coin-holder and anvil and spring-actuated in the opposite direction, means for connecting said rock-shaft to a feeding device, spring-actuated locking mechanism engaging said rock-shaft against the resilience of its spring, an actuating-arm arranged for engagement with a coin, a crank-shaft arranged to engage and oscillate said actuating-arm and a cam on said crank-shaft arranged to release said locking mechanism. 95

7. In a coin-controlled mechanism for cigar-vending machines, a coin-receiver, a latch therefor, a coin-guide below said receiver, a coin-holder and anvil mounted for oscillation with one end traversing the coin-guide, lever mechanism arranged to connect said coin-holder and anvil to a feeding device, a coin-rest adjacent said coin-holder and anvil, an actuating-arm mounted for oscillation and a punch on said arm arranged for engagement with a coin. 100

8. In a coin-controlled mechanism for cigar-vending machines, a coin-receiver, a latch therefor, a coin-guide below said receiver, a coin-holder and anvil mounted for oscillation with one end traversing the coin-guide, lever 105 mechanism arranged to connect said coin-holder and anvil, to a feeding device, a coin-rest adjacent said coin-holder and anvil, an actuating-arm mounted for oscillation and a punch on said arm arranged for engagement 110 with a coin, together with a hook on said actuating-arm arranged to engage said coin-rest and separate it from the coin-holder and anvil. 120

9. In a coin-controlled mechanism for cigar-vending machines, a coin-receiver, a latch 125

therefor, a coin-guide below said receiver, a coin-holder and anvil mounted for oscillation with one end traversing the coin-guide, lever mechanism arranged to connect said coin-holder and anvil to a feeding device, locking mechanism arranged to engage said lever mechanism, a coin-rest adjacent said coin-holder and anvil, an actuating-arm mounted for oscillation and a punch on said arm arranged for engagement with a coin, together with a hook on said actuating-arm arranged to engage said coin-rest and separate it from the coin-holder and anvil.

10. In a coin-controlled mechanism for cigar-vending machines, a coin-receiver, a latch therefor, a coin-guide below said receiver, a coin-holder and anvil mounted for oscillation with one end traversing the coin-guide, lever mechanism arranged to connect said coin-holder and anvil to a feeding device, a coin-rest adjacent said coin-holder and anvil, an actuating-arm mounted for oscillation and a punch on said arm arranged for engagement with a coin, together with a hook on said actuating-arm arranged to engage said coin-rest and separate it from the coin-holder and anvil, and cam mechanism arranged to release said locking mechanism.

11. In a coin-controlled mechanism for cigar-vending machines, a coin-receiver, a magnet in said receiver, a latch therefor, a coin-guide below said receiver, a coin-holder and anvil mounted for oscillation with one end traversing the coin-guide, lever mechanism arranged to connect said coin-holder and anvil to a feeding device, a coin-rest adjacent said coin-holder and anvil, an actuating-arm mounted for oscillation and a punch on said arm arranged for engagement with a coin.

12. In a coin-controlled mechanism for cigar-vending machines, a coin-receiver, a magnet in said receiver, a latch therefor, a coin-guide below said receiver, a coin-holder and anvil mounted for oscillation with one end traversing the coin-guide, lever mechanism

arranged to connect said coin-holder and anvil to a feeding device, a coin-rest adjacent said coin-holder and anvil, an actuating-arm mounted for oscillation and a punch on said arm arranged for engagement with a coin, together with a hook on said actuating-arm arranged to engage said coin-rest and separate it from the coin-holder and anvil.

13. In a coin-controlled mechanism for cigar-vending machines, a coin-receiver, a magnet in said receiver, a latch therefor, a coin-guide below said receiver, a coin-holder and anvil mounted for oscillation with one end traversing the coin-guide, lever mechanism arranged to connect said coin-holder and anvil to a feeding device, locking mechanism arranged to engage said lever mechanism, a coin-rest adjacent said coin-holder and anvil, an actuating-arm mounted for oscillation and a punch on said arm arranged for engagement with a coin, together with a hook on said actuating-arm arranged to engage said coin-rest and separate it from the coin-holder and anvil.

14. In a coin-controlled mechanism for cigar-vending machines, a coin-receiver, a magnet in said receiver, a latch therefor, a coin-guide below said receiver, a coin-holder and anvil mounted for oscillation with one end traversing the coin-guide, lever mechanism arranged to connect said coin-holder and anvil to a feeding device, a coin-rest adjacent said coin-holder and anvil, an actuating-arm mounted for oscillation and a punch on said arm arranged for engagement with a coin, together with a hook on said actuating-arm arranged to engage said coin-rest and separate it from the coin-holder and anvil, and cam mechanism arranged to release said locking mechanism.

Signed by me at Des Moines, Iowa, this 1st day of January, 1902.

CHARLES M. DODSON.
